UNITED STATES PATENT OFFICE.

WALTER OSTWALD, OF GROSSBOTHEN, SAXONY, GERMANY, ASSIGNOR, BY MESNE ASSIGNMENTS, TO THE CHEMICAL FOUNDATION, INC., A CORPORATION OF DELAWARE.

METHOD OF AND APPARATUS FOR UTILIZING MINE WASTE BY MEANS OF THE HEAT OF DUMP-HEAPS.

1,369,350.

Specification of Letters Patent. Patented Feb. 22, 1921.

Application filed July 21, 1916. Serial No. 110,619.

To all whom it may concern:

Be it known that I, WALTER OSTWALD, a resident of Grossbothen, Germany, and citizen of Saxony, have invented certain new and useful Improvements in Methods of and Apparatus for Utilizing Mine Waste by Means of the Heat of Dump-Heaps, of which the following is a specification.

This invention has reference to the utilization of mine waste, that is to say, of rubbish resulting from mining and like operations, such as the heaps of rubbish mainly found in collieries, heaps of oily shale, or any other rubbish heaps of suitable waste. Such heaps which accumulate very rapidly during the process of washing coal or other preliminary treatment always contain very considerable amounts of carbon. Being very closely packed together and frequently penetrated by a good deal of moisture they frequently become heated and self-ignite with the result that they increase in bulk, begin to smoke and make the whole neighborhood smoky. No external heat is usually necessary to start combustion; in some cases, however, on account of the great amount of water poured on the heaps, self-ignition does not occur, and it will be necessary to start combustion by means of a flame. As soon as combustion has started it becomes unnecessary to supply external heat, as the heap will burn out by itself.

Now the present invention has for object to prevent the heat from being wasted and the gases and vapors evolved from injuriously affecting the vicinity and also to enable the metals or metalloids and especially nitrogen contained in the waste material, to be recovered as chlorin compounds, in the form of vapors, the concentration and purification of which can be effected in one and the same operation, by means of the heat derived from combustion of the waste.

Now the principal feature of the present invention consists in the fact that, for the purpose of obtaining non-metals, such as nitrogen, and metals, such as zinc, in the form of chlorids, chlorin compounds are supplied to the mine waste under treatment.

By means of the present invention it is possible to recover up to 80 per cent. of the

nitrogen compounds, contained in the waste product, this being moreover effected by the use of the waste material itself, which by reason of its poor qualities as a fuel has so far been regarded as a useless and mostly even as an injurious waste, although containing from 1.8 to 2 per cent. of combined nitrogen.

By liberally introducing chlorid solution the temperature of combustion of the heap may be kept low and the yield thereby increased, while the metals, and especially the metalloids, are brought into a form which is more convenient for the process of purification. It is, for instance, advisable to recover the combined nitrogen in the form of ammonium chlorid by the process of sublimation. Among the nitrogen compounds which come into consideration, ammonium chlorid has the particular property of passing from points of higher to points of lower temperature without decomposition. I find, moreover, that in some cases the ammonium chlorid is accompanied by sulfur, which may be separated from the ammonium chlorid by dissolving the latter in water. The chlorids such as calcium chlorid used as reagents in the process may be obtained at small cost. Also the presence of deliquescent salts acts favorably upon the process.

In the carrying out of the invention, several pipes are advantageously introduced into the heap, working at the same time that part of the heap which is interposed between the pipes, until said part has given off its valuable contents. The air, steam or water, and chlorid solution required for the operation are introduced into one of the pipes, and the products of evaporation are carried off by the other of the pipes.

Figures 1 and 1^a show in plan and elevation respectively an arrangement for carrying out the present invention in connection with a heap of waste; Fig. 2 shows a double pipe for the same purpose; and Figs. 3 and 4 illustrate cooling arrangements for keeping down the temperature, which arrangements may simultaneously be used for the generation of steam.

The waste heap *a* has introduced into it at definite distances apart, pipes *b* and *c*,

leading to perpendicular pipes *d* and *e* respectively. The pipes *d* and *e* are connected with the main conduits *i* and *f* by means of the valves *g* and *h*. The sodium or 5 other chlorid solution adapted to convert the nitrogen constituents into ammonium chlorid is introduced through the pipes *b*, *i* and *d* and the resulting gas is carried off through the pipes *c*, *e* and *f*. It is advantageous to change the direction of flow 10 from time to time in order to circumvent any kind of obstruction which may take place in the part of the heap between the pipes *b* and *c*. In this manner it is possible 15 to fully utilize the several parts of the heap in a comparatively short time and in an economical manner. Instead of introducing several rows of pipes, double pipes may be introduced into the heap, as shown, for instance, in Fig. 2; the one part *k* of the 20 pipe projecting beyond its other part *m*. The two parts *k* and *m* have openings *l* at their peripheries, so that between these 25 openings a flow of gas and a transformation will take place in the same manner as between the pipes *b* and *c*. Through one of the pipes chlorid solutions are introduced and through the other pipe the evaporation products are carried off. In this case also 30 it is advisable from time to time to reverse the flow.

Besides these pipes which serve for the introduction of air and steam and for carrying off the gases and their by-products, it is 35 advisable to embed special cooling elements into the particular zone under treatment at the time, in order to keep down the temperature and to avoid the production of slag. A 40 simple arrangement for this purpose comprises one or more lower boilers united with an upper boiler, the lower boilers being set in the interior, and the upper boiler upon the surface of the waste field. It is however more advantageous to divide the lower 45 boiler as shown in Figs. 3 and 4, into a number of pipes, in order to obtain greater uniformity in the utilization of the heat. At the burnt-out parts of the waste field the 50 pipes are pulled out and are again inserted at places where new waste material has been deposited. The pipes may be arranged as shown in Fig. 3; the cool water being introduced at *o* and the heated water carried off at *p*; while between those points there are 55 arranged the conduit pipes *q*, which pass through the waste field; *r* and *s* are the valves for closing the several conduit pipes, *t* are the several rotary conveying pumps for 60 regulating the velocity of flow through the pipes according to the temperature of the various parts of the waste field being treated by the respective conduit pipes. In the arrangement illustrated in Fig. 4 the pipes do not pass completely through the waste 65 field but return toward the same side. In-

stead of the return tubes *q*¹ there may advantageously be employed concentric tubes *q*¹¹, of known construction, which may more easily be introduced into the waste heap.

While the invention is mainly designed 70 for the recovery of the zinc and nitrogen present in the waste, it will be understood that the method described is applicable to the recovery of other substances that can be similarly converted into chlorids and then 75 subjected to sublimation or distillation.

What I claim is:

1. The method for the utilization of mine waste by means of heat derived from the 80 burning of said waste, which comprises adding chlorin-containing compounds to the waste, liberating through the utilization of said heat metals and metalloids in the form of chlorids, and recovering the same by condensation.

2. The method for the utilization of mine waste by means of heat derived from the 90 burning of said waste, which comprises adding chlorin-containing compounds in conjunction with water to the waste, liberating through the utilization of said heat metals and metalloids in the form of chlorids, and recovering the same by condensation.

3. The method for the utilization of mine waste by means of heat derived from the 95 burning of said waste, which comprises adding chlorin-containing compounds in conjunction with water in the form of steam to the waste, liberating through the utilization of said heat metals and metalloids in the 100 form of chlorids, and recovering the same by condensation.

4. The method for the utilization of mine waste by means of heat derived from the 105 burning of said waste, which comprises adding water containing chlorids to the waste, liberating through the utilization of said heat metals and metalloids in the form of chlorids, and recovering the same by condensation.

5. The method for the utilization of mine waste by means of heat derived from the 110 burning of said waste, which comprises adding deliquescent chlorin-containing compounds to the waste, liberating through the utilization of said heat metals and metalloids in the form of chlorids, and recovering the same by condensation.

6. An apparatus for the utilization of mine waste by the action of heat, comprising 115 two sets of parallel tubes and separate cooling elements embedded in the glowing waste.

7. An apparatus for the utilization of mine waste by the action of heat, which comprises two sets of parallel tubes in combination 120 with a plurality of cooling elements, said cooling elements being sub-divided into a number of tubes connected in parallel, valves in each of said tubes, and pumps connected with said tubes.

8. In an apparatus for the utilization of
mine waste by the action of heat, a plurality
of cooling elements which are sub-divided
into a number of tubes connected in parallel,
5 valves in each of said tubes, and pumps con-
nected with said tubes.

In testimony whereof I have hereunto

signed my name in the presence of two sub-
scribing witnesses.

WALTER OSTWALD.
